Attorneys.

UNITED STATES PATENT OFFICE.

THOMAS SCOTT WHEATLEY, OF MAHANOY CITY, PENNSYLVANIA.

SHOE-MAKER'S RASPING-TOOL.

SPECIFICATION forming part of Letters Patent No. 320,733, dated June 23, 1885.

Application filed April 25, 1885. (No model.)

To all whom it may concern:

Be it known that I, THOMAS S. WHEATLEY, a subject of the Queen of Great Britain, and a resident of Mahanoy City, in the county of Schuylkill and State of Pennsylvania, have invented certain new and useful Improvements 5 in Shoe-Maker's Raspings-Tools; and I do hereby declare that the following is a full, clear, and exact description of the invention, which 10 will enable others skilled in the art to which it appertains to make and use the same, reference being had to the accompanying drawings, which form a part of this specification, and in which—

15 Figure 1 is a perspective view of my improved rasp or device for removing the projecting ends of pegs from boots and shoes. Fig. 2 is a vertical longitudinal sectional view of the same. Fig. 3 is a horizontal sectional view 20 taken on the line *x x* in Fig. 2, and Fig. 4 is a detail view illustrating parts of the invention detached from each other.

The same letters refer to the same parts in all the figures.

25 This invention relates to that class of devices which are used by shoe and boot makers for the purpose of removing the projecting ends of the pegs from the insides of boots and shoes; and it has for its object to provide a device of 30 this class which shall possess superior advantages in point of simplicity, durability, and general efficiency.

With these ends in view the invention consists in the improved construction and combination of parts, which will be hereinafter fully 35 described, and particularly pointed out in the claims.

In the drawings hereto annexed, A designates an upright or standard, which is provided 40 with rearwardly-extending flanges B B, the upper ends of which form jaws C C, for the reception of a transverse pin, D, on which is pivoted a plate, E, by means of a pair of lugs, F F, extending downwardly from the under side 45 of the said plate. The latter is oval or elliptical in shape, and it is provided in its upper side or surface with a pair of perforations, G G, which are adapted to receive lugs H H, extending downwardly from the rasp-plate I, 50 which latter is secured detachably to the said

plate E by means of the said lugs and a set-screw, J. The said rasp-plate is serrated in the usual manner, or provided with teeth facing in opposite directions, so as to be capable of removing the projecting points of the pegs 55 from the heel or toe, as the case may be.

K is a rod arranged to slide vertically between the flanges B B of the upright A, and the upper end of which is connected pivotally with the under side of the pivoted plate E at 60 the upper end of the upright A, which said plate may, by means of the said sliding rod, be tilted or adjusted to either a horizontal or to an inclined position, as the case may require.

The lower end of the rod K is provided with 65 a forwardly-extending lug, L, extending through a slot, M, formed vertically in the lower end of the upright A, between the flanges B B of the latter, and also through a vertical slot, N, in a slide-plate, O, arranged to move 70 vertically between the lower ends of the said flanges B B. The plate O is also provided with a lug or stud, P, extending through the slot M in the lower end of the upright A. The said lug or stud P forms a foot-piece or treadle, by 75 means of which the device may be conveniently manipulated.

Upon the foot-piece Q, which supports the upright A, with its flanges B B, is mounted a block or upright, R, arranged to bear against 80 the slide-rod K, and to hold the latter in contact with the upright A. The said block, or "guide-piece," as it may be termed, is connected adjustably to the foot-piece Q by means of a bolt, S, working in a slot, T, and it is provided at its upper end with bearings for a longitudinally-sliding bolt, U, forced in a forward direction by a spring, V, and bearing against a pin, W, extending transversely through the said bolt, which latter is thereby adapted to 90 engage any one of a series of perforations, X X, in the sliding bar K, causing the latter to be retained securely in any position to which it may be adjusted.

The slide-plate O is provided with beveled 95 flanges Y Y, as shown, so that by moving the said slide-plate in either an upward or a downward direction the flanges will bear against the pin W and throw the pin or bolt U out of engagement with the slide-rod K, allowing the 100

said rod to be raised or lowered in its desired position.

From the foregoing description, taken in connection with the drawings hereto annexed, the 5 operation and advantages of this invention will be readily understood. The general construction is simple and inexpensive, and the adjustment does not necessitate the removal from the device of the boot or shoe while it is being 10 operated upon.

Having thus described my invention, I claim and desire to secure by Letters Patent of the United States—

1. In a shoe-maker's rasping-tool, the combination of a flanged upright, a plate pivoted to the upper end of the same and having a detachable rasping-tool, a vertically-sliding rod connected pivotally with the said pivoted plate and having a lug at its lower end, a foot block 15 or plate having a sliding pin or bolt adapted to engage perforations in the lower end of the

said sliding rod, and a vertically-sliding treadle-plate having beveled flanges adapted to engage and operate the latch pin or bolt, substantially as and for the purpose herein set 25 forth.

2. In a shoe-maker's rasping-tool, the combination of the flanged upright, the pivoted plate, the slide-rod, the vertically-adjustable and flanged treadle-slide, and the foot-block 30 having a spring-latch adapted to engage perforations in the vertically-sliding operating-rod, and to be operated by flanges upon the treadle-plate, substantially as and for the purpose herein set forth. 35

In testimony that I claim the foregoing as my own I have hereunto affixed my signature in presence of two witnesses.

THOMAS SCOTT WHEATLEY.

Witnesses:
